JOSEPH MENCHEN, OF NEW YORK, N. Y.

DEVICE FOR PHONOGRAFS.

1,317,630.

Specification of Letters Patent. Patented Sept. 30, 1919.

Application filed December 24, 1917. Serial No. 208,660.

To all whom it may concern:

Be it known that I, JOSEPH MENCHEN, a citizen of the United States, and a resident of the borough of Manhattan, in the 5 city, county, and State of New York, have invented a new and useful Device for Phonographs, of which the following is a specification.

In the use of phonographs or talking machines employing flat records inconvenience is experienced in removing the records after playing, because of the difficulty of grasping the thin edge of one of these disks while lying flat upon the surface of the turntable. 10 According to the present invention a flexible suction cup lifting device is provided which operates upon the face of the record, and raises the same sufficiently so that the hand may be placed beneath it. In accordance with one embodiment of the invention the device is mounted upon the swiveled sound box of a laterally swinging and vertically tilting reproducer arm, and in this combination it performs the function of a 15 cushion foot supporting the arm with the sound box off the record while changing needles.

In the drawings:

Figure 1 is a side elevation of a turntable with a record thereon, a reproducer arm and its mounting, the sound box, and a suction cup attachment on the sound box, the last being in its inoperative position and the top of the casing inclosing the mechanism for driving the turntable being shown in section;

Fig. 2 is a view like Fig. 1 with portions broken away and omitted, showing the sound box turned up and the device of the 40 invention upon the record;

Fig. 3 is a vertical section on the line 3—3 of Fig. 2, the sound box being in elevation; Fig. 4 is a sectional plan on the line 4—4 of Fig. 2; and

Fig. 5 is a view partly in vertical section and partly in elevation of a modification.

The turntable 2 is mounted upon a spindle 3 and driven in the usual manner. The reproducer mechanism selected for illustration 50 is of the type wherein the pivotal reproducer arm 4 is bodily movable in the vertical as well as in the horizontal sense, 5 being a horizontal swivel and 6 a vertical swivel, whereby the rear part of the arm is jointed 55 to the fixed neck 7 rising from the cabinet wall 8. As is well understood, the repro-

ducer arm constitutes the initial part of the sound conduit and is connected through the fixed part 7 with an amplifier beneath the record support. A sound box 9 is swiveled 60 upon its axis on the forward end of the arm so that it may be turned in a vertical plane. In the position of Fig. 1 its stylus 10 rests upon the record, while in Fig. 2 it is turned upward to facilitate exchange of needles. 65

The lifting device comprises a flexible suction cup 11, of such diameter and resiliency of wall as to secure a purchase upon the face of the record 12 when pressed thereon sufficient to enable the disk to be 70 lifted through the agency of the cup, so that it may be conveniently grasped by the hand not engaged in operating the cup. As indicated in Fig. 4 the cup is best applied toward one side, partly on the smooth part of 75 the record and partly upon the grooves, as at this region it secures a sufficiently firm grip and at the same time is self-releasing when the record has been raised a certain distance, the vacuum in the cup becoming 80 broken partly by the leverage of the record and partly by the grooves acting as channels to admit air slowly.

The cup is preferably, though not necessarily, secured to the sound box 9. For this 85 purpose it is shown provided with a substantially U-shaped spring clip 13 having an anchoring stem portion 14 which is vulcanized in the top of the cup. The limbs 15 and 16 of the clip are formed and spaced 90 in such manner as to embrace and clasp the edge of the sound box, and the limb 15 at the face or diaphragm side of the box is formed with a punched toe 17 to engage over the internal shoulder 18 of the rim of 95 the box. The stem portion in this instance is formed by two pieces which are partially cut out of the limbs 15, 16 and bent downward therefrom, leaving the openings 19, the extremities 20 of the pieces being turned 100 out as shown.

The cup preferably projects from the periphery of the box at somewhat more than a quadrant's distance from the stylus holder 21, so that when the box is turned to dispose the needle in a convenient, upwardly and forwardly inclined position, for changing, the suction cup is brought down upon the record. In this operation the reproducer arm is also tilted upward about its 105 swivel 6, as seen in Fig. 2. The cup may thus serve as a non-marring foot to support 110

the sound box and arm during the changing of the needle. In order to lift the record, the pivotal arm and suction cup are depressed, thereby flattening the cup and expelling air therefrom, so that when the pressure is removed the partial vacuum produced by the effort of the resilient cup to resume its normal form causes the cup to hold firmly to the surface of the record. If 5 now the cup be raised, by tilting the reproducer arm upward or otherwise, the record is also raised, and may be readily grasped and removed as heretofore explained. Manifestly the device may also be used to 10 support the sound box with its needle upwardly presented, by resting upon the cabinet top at one side of the record.

In Fig. 5 a modification is shown, wherein a valve 22 is provided in the cup 11^a for facilitating the breaking of the vacuum. This valve may comprise a stem slidable in a bushing 23 vulcanized in the top of the cup and having a conical head 24 coöperating with a corresponding valve seat recess in 25 the lower end of said bushing. An expansion spring 25 interposed between the top of the bushing and a clip 13^a or other suitable head to which the valve stem is united seats the valve. This spring may be sufficiently strong relatively to the resistance of 30 the walls of the cup to distortion, so that the valve will not be unseated by downward pressure sufficient to grip the cup upon the record, or its action may be more rapid than 35 the resilience of the cup so that though unseated by pressure, if this pressure be quickly removed the valve will close before the cup can resume its original form. For purpose of further illustration the clip 13^a is represented as of rigid form. The extremity of the arm 15^a is turned in to form a holding toe 17^a, and the other arm bears a set-screw 26 to bear against the back of the sound box. 40

45 While I have described the preferred form and mode of application of my invention, it will be understood that numerous other embodiments are possible.

What I claim as new is:

50 1. In a phonograph having a turntable record support, record-lifting means comprising an overhanging arm, and a flexible suction cup thereon movable toward and from the turntable, said cup having a flexible open mouth and depending upon its collapsibility for its suction effect.

2. In a phonograph having a turntable record support, record-lifting means comprising a pivotal arm, and a flexible suction 55 cup movably jointed to the pivotal arm, so as to be movable into and out of suction engagement with a record on the turntable, said cup having a flexible open mouth and depending upon its collapsibility for its suction effect.

3. In a phonograph having a turntable record support, a record-lifting means comprising an arm adapted to overhang the turntable, means mounting the same upon a fixed part of the phonograph with capacity for lateral swinging and vertical tilting, a flexible suction cup, and means pivotally connecting the same to the arm, said cup having a flexible open mouth and depending upon its collapsibility for its suction effect. 75

4. In a phonograph, the combination with a turntable and a reproducer arm, of a flexible suction cup device mounted on the reproducer arm for lifting records from the turntable. 80

5. In a phonograph, the combination with a swinging and tilting reproducer arm, of a flexible suction cup pivotally mounted on said arm for lifting the records.

6. In a phonograph, the combination with a swinging and tilting reproducer arm, and a sound box swiveled thereon, of a flexible suction cup secured to the sound box and adapted to be brought upon the record when the stylus is turned up. 90

7. In a phonograph, the combination with a reproducer arm and a sound box pivotally jointed thereon, of a flexible suction cup on the sound box adapted to be brought upon the record. 95

8. A record-lifting attachment for phonographs, comprising a flexible suction cup and means for attaching the same to the reproducer mechanism in such manner as to enable it to lift a disk record through movement of the reproducer mechanism. 100

9. A record-lifting attachment for phonographs, comprising a flexible suction cup and a clip connected to the cup and constructed to engage a sound box whereby through movement of the sound-box the cup may be caused to grip and lift the record. 105

10. A record-lifting attachment for phonographs, comprising a flexible suction cup and a clip connected to the cup and constructed to engage a sound box, said clip comprising two limbs adapted to embrace the edge of the sound box, one limb having a toe to take over the rim at the face of the box. 110

11. A record-lifting attachment for phonographs, comprising a flexible suction cup and a clip connected to the cup and constructed to engage a sound box, said clip comprising a substantially U-shaped element 120 adapted to embrace the edge of the sound box and having means upon its limbs for securing thereto, and a stem part consisting of portions struck out of the limbs and bent below the base of the U-shaped element 125 and embedded in the material of the cup.

12. A record-lifting attachment for phonographs, comprising a flexible suction cup and a substantially U-shaped spring clip secured to the cup and adapted to embrace the edge 130

of the sound box, whereby through movement of the sound-box the cup may be caused to grip and lift the record.

13. In a disk-record phonograph, the combination with reproducer mechanism of the type comprising a laterally swinging reproducer arm free to gravitate and a vertical sound-box swiveled on said arm and carrying a stylus-holder adapted to be turned upward by swiveling the sound-box on the gravitating arm, of a cushion foot mounted on the periphery of the sound-box in such relation to the stylus-holder as to support the reproducer mechanism upon the record when the sound-box is turned to bring the stylus-holder upward into convenient position for changing the stylus.

14. In a disk-record phonograph, the combination with a reproducer mechanism of the type comprising a swinging and tilting 20 reproducer arm and a vertical sound-box swiveled upon its axis on said arm and carrying a stylus-holder, of a cushion foot mounted on the periphery of the sound-box in such relation to the stylus-holder as to support 25 the reproducer mechanism upon the record when the sound-box is turned to bring the stylus-holder upward into convenient position for changing the stylus, said foot comprising a suction cup adapted to lift the 30 record by raising of the reproducer mechanism.

JOSEPH MENCHEN.
